UNITED STATES PATENT OFFICE.

JOSEPH C. FERGUSON, OF WASHINGTON, DISTRICT OF COLUMBIA.

HYDROCARBON BURNER.

Application filed January 16, 1924. Serial No. 686,600.

To all whom it may concern:

Be it known that I, JOSEPH C. FERGUSON, a citizen of the United States, residing at Washington, in the District of Columbia, 5 have invented certain new and useful Improvements in Hydrocarbon Burners, of which the following is a specification.

This invention relates to certain improvements in hydrocarbon-burners and it is an 10 object of the invention to provide a novel and improved device of this general character adapted for use in connection with furnaces, boilers and the like.

It is also an object of the invention to 15 provide a novel and improved device of this general character wherein the liquid fuel is vaporized together with means for spreading or distributing the flame in a manner to obtain maximum heating efficiency.

20 An additional object of the invention is to provide a novel and improved device of this general character wherein the liquid fuel is converted into gas before being discharged from the burner and wherein is 25 employed a regulatable fuel supply means.

The invention consists in the details of construction and in the combination and arrangement of the several parts of my improved hydrocarbon-burner whereby certain 30 important advantages are attained and the device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein:—

40 Figure 1 is a view partly in section and partly in elevation illustrating a burner constructed in accordance with an embodiment of my invention and in applied position, the adjacent portions of a furnace being diagrammatically indicated by broken lines;

45 Figure 2 is a view in top plan of the burner as herein disclosed, the pipe lines associated therewith being omitted;

Figure 3 is a sectional view taken substantially on the line 3—3 of Figure 1, with certain of the parts in elevation;

50 Figure 4 is a view partly in elevation and partly in section of the device herein dis-

closed in applied position, certain of the parts of the furnace being indicated by broken lines, the device being arranged at substantially a quarter turn with respect to the illustration in Figure 1. 60

My improved burner is adapted to be positioned within the fire box of a furnace or the like and comprises a base B which is positioned directly upon and supported by the grate G diagrammatically indicated by broken lines in Figures 1 and 4. 65

The base B has its central portion raised, as at 1, to provide a chamber 2 open at its lower end. The side wall of the chamber 2 at a predetermined point above its lower open end is provided with an annular shoulder 3 providing an abutment for a plate 4 intersecting the chamber 2 in a horizontal direction. The plate 4 may be held in applied position in any desired manner but 70 as herein disclosed the holding screws 5 are employed.

The central portion 6 of the plate 4 is imperforate and said imperforate portion is substantially defined by an upstanding continuous flange 7 resulting in the formation of a cup to receive liquid fuel which may be dropped from the burner proper in the event the flame should be extinguished. Leading from the cup 7 is a pipe 8 which 75 preferably extends exteriorly from the furnace or the like through the ash pit as is illustrated in Figure 1 of the accompanying drawings. This pipe 8 is preferably intended to lead to a mechanism for automatically shutting off the feed valve for the burner proper under such conditions. However, as this mechanism forms no part of the present invention an illustration or description thereof is believed unnecessary. 80 85 90 95

The top wall 9 of the base B is provided with a relatively large central opening 10 defined by an upstanding continuous flange 11 of desired length whereby a draft flue 12 is provided, the air circulation being upwardly from the ash pit of the furnace or the like, through the openings 12 in the portions of the plate 4 outwardly of the imperforate portion 6 and especially through the flue 10, as is indicated by the arrows in 100 Figures 3 and 4.

Leading from a suitable source of fuel supply is a pipe line L. This line L extends within the ash pit of the furnace or the like and is then continued upwardly through 105 110

grate G and through a suitable opening 14 provided in a marginal portion of the base B. The end portion of the line L within the furnace and above the grate G is coupled, 5 as at 15, to a horizontally disposed coil 16. The coil being herein disclosed as comprising substantially a single convolution and which has its bore of a diameter considerably in excess of the diameter of the line L 10 or more particularly that portion of the line immediately adjacent to the coil.

The end portion of the coil 16 remote from the coupling 15, is coupled, as at 17, to an upstanding pipe 18 having its bore of 15 a diameter substantially the same as the diameter of the bore of the coil 16. The upper portion of the pipe 18 is coupled, as at 19, with an inwardly disposed pipe 20 which has its inner end portion coupled, as at 21, 20 to a depending pipe 22. The bore of the pipe 20 is materially less than that of the pipe 18 and as herein disclosed, the bore of the pipe 22 is of a diameter greater than that of the pipe 18. By reducing the bore 25 of the pipe 20 the vaporized fuel or gas is caused to enter and pass through the pipe 22 with increased force whereby the efficiency of the device is materially increased.

The lower end portion of the pipe 22 is 30 coupled or connected, as at 23, with the upper portion of a hollow burner member 24, said member 24 being herein disclosed as substantially in the form, in cross section, of a triangle with its apex downwardly disposed and positioned at substantially the axial center of the opening 10. The walls of the member 24 at the upper portion thereof are provided with the jet openings 25 where the vapor or gas is ignited. These openings 35 40 25, as is clearly illustrated in Figures 3 and 4 are arranged within the field defined by the coil 16 so that the flame or blaze will effectively heat the coil 16 to convert the liquid fuel into the desired gas or vapor. 45 The upper portion of the burner member 24 is defined by the upwardly disposed and abruptly flared spreader flange 26 which operates further to assure the proper action of the flame or blaze upon the coil 16 and also 50 to distribute the flame or blaze within the fire box of the furnace to assure a maximum of heating efficiency and more particularly when the burner is employed in connection with a hot water or steam heating system 55 although I do not wish to be understood as limiting myself to any particular use of my improved burner.

In order to increase the strength of the 60 assembled device and to maintain the same effectively in assembled relation the flange 26 is connected at desired points with the upper wall 9 of the base B by the bolts 27, each of said bolts being surrounded by a spacer sleeve 28 interposed between the wall 65 9 of the base B and the flange 26. Each of

the bolts 27, as herein disclosed, also has interposed between the upper surface of the flange 26 and the holding nut 29 a spacer sleeve 30.

Arranged within the line L at a point exterior of the furnace or the like is a needle valve 31 serving to regulate the flow of the liquid fuel from the source of supply to the coil 16 and in practice, I find it of special advantage to adjust the valve 31 in a manner 75 whereby the liquid fuel will pass the valve in drops as I have fully demonstrated in actual practice that the feed of this kind results in the burner operating to the best advantage and in a manner whereby the waste 80 of fuel is substantially eliminated.

In practice, the flame or blaze from the jet openings 25 is further distributed within the fire box through the medium of the draft passing through the flue 10, such draft, also 85 supporting combustion in a manner whereby smoking and the like is avoided.

When the assembled device is applied within the fire box of a furnace or the like the portions of the grate outwardly of the 90 raised portion 1 of the base B and the side walls of the furnace are closed or sealed, as at 32, preferably by asbestos cement.

The coil 16 may be initially heated in any manner preferred but as herein disclosed the 95 flue 11 is surrounded by a gas burner 33 in communication through the pipe 34 with a suitable source of gas supply, said pipe 34 being disposed through a suitable opening 35 produced in the peripheral portion of the 100 base B and extending exteriorly of the furnace or the like through the ash pit, as is clearly indicated in Figure 1 of the accompanying drawings.

From the foregoing description it is 105 thought to be obvious that a hydrocarbon-burner constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as 110 limiting myself to the precise arrangement and formation of the several parts herein shown in carrying out my invention in practice except as hereinafter claimed.

I claim:

1. A device of the class described comprising a base provided with a chamber having opposed openings, one of said openings being continued by a flue, a coil positioned outwardly of the flue adapted for communication with a supply of liquid fuel, a burner positioned above the flue and in communication with the coil, a plate disposed within the chamber of the base and underlying the opening continued by the flue, the marginal 125 130

portion of the plate being perforated, the central portion of the plate being provided with a collecting cup.

2. A device of the class described comprising a base provided with a chamber having opposed openings, one of said openings being continued by a flue, a coil positioned outwardly of the flue adapted for communication with a supply of liquid fuel, a burner positioned above the flue and in communication with the coil, and a plate disposed within the chamber of the base and underlying the opening continued by the flue, said plate being provided with a collecting cup.
3. A device of the class described comprising a base provided with a chamber having opposed openings, one of said openings being continued by a flue, a coil positioned outwardly of the flue adapted for communication with a supply of liquid fuel, a burner positioned above the flue and in communica-

tion with the coil, and a plate disposed within the chamber of the base and underlying the opening continued by the flue, the central portion of the plate being provided with an upstanding continuous flange providing a receiving cup. 25

4. A device of the class described comprising a base provided with a chamber having opposed openings, one of said openings being continued by a flue, a coil positioned outwardly of the flue and adapted for communication with a supply of liquid fuel, a hollow burner positioned outwardly of the flue and in communication with the coil, said burner being substantially triangular in cross section with its apex disposed toward the flue, the wall of the burner adjacent its upper end being provided with a series of circumferentially disposed jet openings. 30 35 40

In testimony whereof I affix my signature.

JOS. C. FERGUSON.
